HOUSE CAR DOOR CONSTRUCTION

Filed April 28, 1928

Fig. 1.

UNITED STATES PATENT OFFICE

FRANK DITCHFIELD, OF CLEVELAND, OHIO, ASSIGNOR TO THE YOUNGSTOWN STEEL DOOR COMPANY, OF CLEVELAND, OHIO, A CORPORATION OF OHIO

HOUSE-CAR-DOOR CONSTRUCTION

Application filed April 28, 1928. Serial No. 273,479.

This invention relates to improvements in house car door construction.

In the operation of box and automobile cars, commonly termed "house cars", it is essential that a tight weather and spark seal be maintained between the side doors and the associated parts of the car wall. Many arrangements for this purpose have heretofore been suggested but, so far as I am aware, all 10 have been characterized by the fact that the sealed joint has been dependent upon two members only, one affixed to the door posts or equivalent member and the other to the door. In such prior arrangements, great difficulty has been experienced in maintaining the line of sealing contact, due to unavoidable variations inherent in the fabrication and application of the parts, and, more especially, to injuries to the sealing elements occurring in service from the use of sledges, 15 pry bars and other tools forcing the doors open and closed.

One object of my invention is to provide a weather and spark sealing construction for 20 slidable doors of house cars which will definitely comprise at least two independent lines of sealing contact, one supplementary to the other, to the end that, if failure of sealing contact occurs at any portion in one line of 25 contact, the other line of contact opposite thereto will act as a safeguard to prevent entrance of moisture or sparks to the interior of the car.

Another object of my invention is to provide 30 a door sealing arrangement which includes three elements so arranged as to constitute two distinct lines of sealing contact therebetween, thus compelling any foreign matter to pass first one and then the other before possibility of gaining admission to the interior of the car.

Other objects of my invention are: To provide 35 a sealing arrangement for car doors wherein an air pocket or trap associated with a double line of sealing engagement between the sealing elements; to so construct and apply the cooperating sealing elements to the door and car body that the sealing member on the door, particularly, is braced and reinforced to prevent danger of warping,

denting or distortion; to so arrange the sealing elements that they will automatically cooperate to yieldingly pull the door closely against the faces of the door framing members when the door is in closed position to thereby eliminate vibration and rattling; and to otherwise increase the efficiency and long life of constructions of the character indicated.

In the drawing forming a part of this specification, Fig. 1 is a side elevational view of a portion of the side wall of a box car showing my improvements in connection therewith, parts being broken away to prevent crowding of the drawing. Fig. 2 is a horizontal sectional view corresponding to the line 2—2 of Fig. 1, upon an enlarged scale, parts being broken away in this view also, for the same purpose. And Figs. 3 and 4 are detail horizontal sectional views of two other sealing arrangements embodying my invention.

Referring first to the construction illustrated in Figs. 1 and 2, the side wall of the box car is indicated generally by the reference character 10, the usual side door opening 75 thereof being defined by a Z-bar front door post 11 and a rear Z-bar door post 12, wood fillers 13—13 being secured thereto in the usual manner.

The particular type of door which I have chosen for illustration is of the sheet metal type and designated generally by the reference character A. Said door preferably comprises a plurality of sheet metal panels having horizontally extending corrugations 85 14—14 which merge at their ends with vertical edge corrugations 15 and 16. Each of the vertical corrugations is bridged and reinforced on its inner side by a bridging strip or plate 17, the strip 17 at the forward edge 90 of the door preferably being extended around the front marginal edge of the main sheets as indicated at 18, whereby to give a triple-ply flat marginal edge for the front of the door, the latter being adapted to enter a recess provided by the outer flange 19 of the Z-bar post 11 and a flange 20 of an angle 21 which is secured to said post. The vertical corrugations are also preferably reinforced by inlaid plates or strips 22 riveted thereto 100

as indicated in Fig. 2. The door may be hung in any suitable manner, top roller brackets 23 being shown.

Referring to Fig. 2, the door A has the rear vertical edge thereof reinforced, braced and stiffened by a buffer angle 24, one flange 25 of which lies against the outer face of the double-ply marginal edge of the door and is riveted thereto by the vertical series of rivets 26. The other flange 27 of the angle projects inwardly beyond the edge of the door proper and is designed to receive the blows of the door against the back stops and of the sledges and pry bars that are frequently used in service.

The sealing of the door with respect to the car wall is effected by three elements 28, 29 and 30, in the form of the invention illustrated in Fig. 2.

20 The sealing element 28 comprises a strip of fairly heavy metal which is obtuse in cross section and extends approximately the entire height of the door. Said strip has a base flange or section 31 riveted to the inner face 25 of the margin of the door proper, the rear edge of said flange 31 preferably abutting the flange 27 of the buffer angle so that, when a blow is applied to the buffer angle, the rivets 26 which secure both the strip 28 and 20 angle to the door, are placed under double shear, thus increasing the strength of the connection. The sealing strip 28 also has a forwardly and inwardly extending free edge flange 32 adapted to cooperate with the other 25 two elements 29 and 30.

20 The sealing member 29 is in the form of an angle having one flange 33 thereof secured to the web of the post 12 by a series of rivets 34. The other flange 35 of said angle 29 is arranged parallel to the door and flush with the outer flange of the Z-bar post 12, said flange 35 having its free edge projecting rearwardly, as shown in the drawing.

45 The third sealing element 30 is in the form of a preferably formed strip of somewhat lighter sheet metal than the strip 28, said strip 30 being also of obtuse angle in cross section and having a securing base or flange 36 and a rearwardly and outwardly projecting, free edge flange 37. The element 30 is inwardly offset with respect to the flange 35 and is secured to the post 12 by the same series of rivets 34.

55 With the construction thus described, it will be seen that a line of sealing contact is provided at 38 between the free edge of the flange 35 and an intermediate portion of the flange 32 of the sealing strip 28. A second line of sealing contact spaced therefrom is 60 provided as indicated at 39 between the overlapping free edges of the sealing elements 30 and 28. In addition, there is a triangular air pocket 40 formed by the three sealing elements as shown in Fig. 2.

65 With the construction described, it is evi-

70 dent that before any moisture or sparks can enter the car, the same must first pass the line of sealing contact 39. Should this occur, the foreign matter will then be within the air pocket 40 and be trapped therein and drained out, it being well understood that there will always be a current of air in such pocket when the car is in motion. The moisture or sparks cannot, of course, enter the car without passing 75 the second line of sealing contact 38.

75 All of the sealing elements will have more or less inherent resiliency, the strip 30 being the least flexible. Due to the sloping overlapping of the flanges 32 and 37, and also on account of the wedging arrangement between the flange 32 and flange 35, there is an automatic resilient tension exerted on the door tending to pull the same inwardly toward the car side and hence into close contact with the face of the door-forming elements. In actual 80 practice, it is very difficult to eliminate camber in elongated members such as are employed in obtaining sealed joints for car doors and there are also necessarily certain variations or tolerances in the manufacture of 85 such elements. Under such conditions, it is extremely difficult, when the parts are applied to the car wall and door, to insure an absolutely perfect continuous line of contact, there being intervals where the parts will not form 90 a true seal. This is further accentuated in service by the weaving of the car superstructure and the injuries that occur to the parts in opening and closing the door. With my construction, where two independent and 95 definite lines of sealing contact are provided, the possibility of there being gaps in the lines of contact directly opposite each other is extremely remote and should there be a gap in one line of sealing contact, there is the practical safeguard of the secondary line opposite thereto, thus insuring a practically perfect seal under any ordinary conditions of 100 service.

100 Referring to the construction shown in Fig. 3, the door proper is constructed the same as that of the first described form and said door has a similar buffer angle 124 and a similar sealing strip 128 secured to its rear edge in the same manner as heretofore described. 115 In this construction, the rear door post 112 is specially formed and designed primarily for house cars having metal side walls 110. Said post 112 has the outer flange thereof 120 extended first perpendicular to the car side, as indicated at 50 and is then bent rearwardly to provide the flange 135 parallel to the door and with the free edge thereof projecting rearwardly. To the web of the post 112 and within the corner pocket formed by the sections 50 and 135 is secured the third sealing element 130, the same being preferably in the form of a rolled or formed strip with a securing base section 136. Said strip is bent so as 125 to provide a narrow section 51 bearing against 130

the post section 50 and is then bent rearwardly and outwardly to provide the free flange 137 cooperable with the forwardly and inwardly extending flange 132 of the sealing strip 128.

5 As will be evident, two lines of sealing contact are provided between the three elements, one at 138 and the other at 139, the former being between the flange 135 of the post and the sealing strip 128, and the latter between the sealing strip 130 and sealing strip 128. An air pocket is provided as in the first described form.

In the construction of Fig. 4, the rear door post 212 is constructed as in the modification of Fig. 3 and has the outstanding section 250 and outer flange 235. A similar sealing strip 230 is secured to the post, said strip having a rearwardly and outwardly extending flange 237.

15 The door proper in this form is the same as in the other constructions and has secured thereto a similar buffer angle 224.

The sealing strip 228 applied to the rear 25 edge of the door is somewhat different from the other corresponding strips 28 and 128. Said strip 228 has the securing base flange 231, an inwardly and forwardly extending section 232, the latter terminating in a 30 straight edge flange 53 disposed parallel to the door.

With this construction, two lines of sealing contact are obtained as before, the same being indicated at 238 and 239. An air pocket 35 240 is also provided and a supplementary air pocket 54.

With this construction, the co-action of the flange 235 and sealing strip 228 is the same as in the other constructions. The action between the straight edge 53 and the flange 237 40 of the third sealing member is, however, somewhat different, said flange 53 bearing against the flange 237 and tending to bend the latter outwardly rather than to slide up thereon.

45 Should the relation of the three sealing elements be such that, as the door is forced to closed position, the movement is not positively limited by engagement of the flange 235 and section 232, the door will nevertheless be 50 limited in its closing movement by the flange 237 of the third sealing member being bent down into contact with the flange 235 of the door post.

55 Although I have herein shown and described what I now consider the preferred manner of carrying out my invention, the same is merely illustrative and I contemplate all changes and modifications that come within the scope of the claims appended hereto.

60 I claim:

1. In a house car door construction, the combination with a fixed wall member; of a door member; and devices providing a double seal between said members, said devices including: A sealing strip carried by one of

said members, and cooperable means carried by the other of said members, said means having two separate sections each adapted to independently contact said strip on the same surface along spaced lines.

70 2. In a house car door construction, the combination with a fixed wall member; of a door member; and devices providing a double seal between said members, said devices including: A sealing strip carried by the door member, and cooperable means carried by the wall member, said means having two separate sections each adapted to independently contact said strip on the same surface along spaced lines.

75 3. In a house car door construction, the combination with a fixed wall member; of a door member; and devices providing a double seal between said members, said devices including: A sealing strip carried by one of said members, and two independently formed elements each having a projecting flange carried by the other of said members, said flanges being adapted to contact with said strip, said strip overlying the free edges of both of said flanges when the door is closed.

80 4. In a house car door construction, the combination with a fixed wall member; of a door member; and devices providing a double seal between said members, said devices including: A sealing strip carried by the door member, and two independently formed elements each having a projecting flange carried by the wall member, said flanges being adapted to contact with said strip, said strip overlying the free edges of both of said flanges when the door is closed.

85 5. In a house car door construction, the combination with a door post having a flange at its outer portion rigid with respect thereto and extending parallel with the car side, said flange projecting rearwardly; a door having a cooperable sealing strip secured to the rear edge thereof, said strip having a flange projecting inwardly and forwardly 90 and beyond the free edge of said first named flange, the inner face of the strip flange being engageable with said free edge; and additional means carried by said post engageable with the inner face of said strip flange near the free edge of the latter.

95 6. In a house car door construction, the combination with a door post having a flange at its outer portion rigid with respect thereto and extending parallel with the car side, said flange projecting rearwardly; a door having a cooperable sealing strip secured to the rear edge thereof, said strip having a flange projecting inwardly and forwardly 100 and beyond the free edge of said first named flange; and additional means carried by said post engageable with said strip flange near the free edge of the latter, said means comprising a metal strip with a rearwardly and outwardly extending resilient flange.

7. In a house car door construction, the combination with a side door post; of an angle secured thereto and having one of its flanges projecting rearwardly and parallel with the car side; a door having a sealing strip on its rear edge, the strip having a section extending forwardly and inwardly; and a second metal sealing strip having a flexible flange secured to said post and disposed inwardly of said flange of the angle, said forwardly and inwardly extending section of the door strip being adapted to engage said angle flange and the flexible flange of the post strip when the door is in closed position.
8. In car construction, the combination with a car side provided with a door opening and having a Z-bar post at the rear side of the opening, said Z-bar having the web thereof extending perpendicular outwardly from the car side; of a door adapted to close said opening; and weather-sealing means carried by said post and door including a metal strip carried by the door having a forwardly and inwardly extending flange, an angle secured to the web of said Z-bar post and having one flange projecting rearwardly and a sealing strip also secured to the web of said Z-bar post inwardly of said angle and having a flange projecting rearwardly and outwardly, the door strip flange being engageable with said angle flange and last named sealing strip flange.

In witness that I claim the foregoing I have hereunto subscribed my name this 31st day of March, 1928.

FRANK DITCHFIELD.
